UNITED STATES PATENT OFFICE.

AMOS C. BARSTOW, OF PROVIDENCE, RHODE ISLAND.

DESIGN FOR STOVES.

Specification forming part of Design No. **11,515**, dated November 18, 1879; application filed October 17, 1879.
[Term of patent 7 years.]

To all whom it may concern:

Be it known that I, AMOS C. BARSTOW, of the city of Providence, Rhode Island, have invented a new and useful Design for Stoves, which design is fully set forth in the following specification.

The design is that of an upright base-burning stove. The body or main portion is a many-sided prism, surmounted by a frustum of a pyramid, and this by a dome circular in its horizontal sections, and forming a portion of an ellipsoid or paraboloid of revolution. The whole is capped by a many-sided vase. At the bottom is a platform of polygonal exterior shape, resting on feet which are themselves angular upon their face. Extending around the stove are three overhanging projections or rings, all beveled on the outside, of which the lowermost is circular, and divides the prismatical part into two portions; the second polygonal, dividing the prismatical from the pyramidal part; and the uppermost, which is at the top of the latter, circular. There are three sets of doors, which agree in general outline with that part of the stove to which they are attached. The lower set are solid, and ornamented as described below. The middle set are mica-glazed, with a single row of lights, and fill the space between the lower and middle projections. Each aperture in the frame is substantially square, and at each corner is a small rectangular re-entrant projection, and in the frame is an ornament, extending on the contiguous sides of the aperture.

The upper set of doors are mica-glazed, and extend about two-thirds of the distance from the middle to the upper projection. They are narrower at the top, and the upper corners are cut off. Each door is divided into three panels, each section being Gothic-shaped, or of an ogee form, divided by two angular bars, crossed, to leave a diamond or parallelogram shaped opening between. Around the top and at the lower corners of the panels are small ornaments.

The pyramidal part above the doors is ornamented in the Japanese style. The dome is ornamented in the Moresque style. At its base is a plain many-sided frustum of a pyra-

mid, upon which a plate may be secured bearing the name of the stove or design. In this case it is marked "Regalia." The vase supports an ornamental top piece, which covers the mouth of it. The lower solid doors, which give access to the ash-pit, are ornamented with stars, surrounding a medallion inclosing a small cross ornament, and the lower portion of the prismatical part is ornamented in a similar way.

Just below the lowermost circular projection or ring is a small running border. At the bottom of the prismatical part is a plain polygonal border, from which an inclined conically-shaped base, ornamented in the Moresque style by a wavy line and a fleur-de-lis-like ornament, slopes outward and joins the supporting-platform. About this latter is a plain ring supported in an elevated position, which serves as a foot-rest.

The feet, on their inclined upper faces, are ornamented with a wavy or zigzag line and a fleur-de-lis-like device, and on the face below is impressed a letter, in this case "R," from "Regalia," as the design is called.

At the back of the stove is an extension, forming a chimney or outlet for the products of combustion, around which the two lower projections extend, and the different portions of which are ornamented similarly to the adjacent parts, to form a harmonious whole.

This stove is shorter in proportion to the diameter of the fire-chamber than is usual in stoves of the same class.

I claim—

1. The design of a base-burning or magazine stove, consisting of the different parts, of the shape and configuration shown and set forth.

2. The design consisting of the different parts of the configuration shown, combined with their ornaments, as shown and set forth.

In testimony whereof I have signed this specification in the presence of two subscribing witnesses.

A. C. BARSTOW.

Witnesses:

A. POLLOK,
C. J. HEDRICK.
